United States Patent Office.

FRANCIS XAVIER RIZY, OF MONROE, MICHIGAN.

Letters Patent No. 64,148, dated April 23, 1867.

MUSICAL RACK OR DESK.

The Schedule referred to in these Letters Patent and making part of the same.

TO WHOM IT MAY CONCERN:

Be it known that I, FRANCIS XAVIER RIZY, of Monroe, Monroe county, and State of Michigan, have invented a new and useful improvement in Music Racks or Desks, of which the following is a full and exact description.

The nature of my invention consists in making a desk or rack for music attached to a piano, melodeon, organ, or other like instrument, movable, either in an inclined direction or horizontal, according to the height of the instrument, by means of bars crossing each other at angles varying with the movement. These cross-bars may be made of metal, wood, or other material, and fastened between clamping-bars, by screws passing through the ends of the cross-bars, and the whole fastened to the top front of the instrument in the usual place.

The object of my invention is to adapt the distance and position of the music to the focal distance of the eye of the performer, without constraining the body by bending forward or backward, or crouching, to read the lower lines, and also to keep the inclination of the book or sheet always the same to the line of vision. In the accompanying drawings—

Figure 1 is a top view, in perspective, with the apparatus closed.

Figure 2, the same with the apparatus open and the music support or rack down.

Figure 3, an end view plane, showing the desk open and the movement in the line of vision.

Figure 4, a pair of cross-bars, inverted, in perspective.

Figure 5, one of the cross-bars, side view.

Figure 6, a sectional view of the inner surface of the two lower clamping-bars, showing the slots in which the ends of the cross-bars work.

Similar letters of reference are for like parts.

A, fig. 1, is the top of the piano, where the desk is fastened. *b* is the foot of the desk, which is fastened to the piano; *c* the music rack, which, when up in position, supports the music; *d* the foot-board on which the music rests; *e* the clamping-bars, in which act the ends of the cross-bar; *f* the thumb-screws to fasten the cross-bars in position; fig. 2, *G G G*, the cross-bars extended; *h* an inclined plane, on which rests the broad lower rear clamping-bar, and to which it is fastened; *i*, recesses cut into the bars, to take in the thumb-screw when the desk is closed; *j j* the stanchions in which revolve the axles of the music rack *c*. *k*, fig. 3, is the line of vision as it strikes the music on this improved desk in all positions, whether closed or fully extended, which is not the case in the common movable desk; *l* the new position that the eye must be lowered to in using the common movable desk when brought forward; *m* the point at which the line of vision would strike the music if not so lowered; *n n* the enlargements at the ends of the cross-bars to fill up between the clamping-bars; *o*, fig. 5, the spur or lug that works in the slots to guide the cross-bars; *p*, fig. 6, the slots in the clamping-bars. Fig. 1 represents the desk closed, the rack down, ready to put down the piano lid, while fig. 2 shows it drawn out, but the rack down, which, when in use, will be raised in the usual manner, as seen in fig. 3. To use this desk it is only necessary to take hold of the foot-board *d* and pull out to the proper focal distance, and if desired turn the thumb-screw *f* to fasten it there. The clamping-bars *e*, which take in the ends of the cross-bars *G*, may be made of thin strips of metal, or any other proper material, and may also be lacquered or painted in imitation of any of the woods, or enamelled and mounted with pearl, &c., on the outside; but the working sides must be made very true and highly polished, in order to insure easy working. The inclination of the inclined plane *h* may be made at the usual angle of the rack itself, or, rather, at right angles to it, when the cross-bars of course will project forward in the same line as seen in fig. 3, travelling always in the line of vision *k*. The cross-bars *G* should be half cut away in thickness, except at the ends *n*, as seen in fig. 4, in order to work across each other and shut within the clamping-bars *e*. The lower clamping-bars must have slots, *p*, as seen in fig. 6, in which work the pins or spurs *o*, as seen in figs. 4, 5, 6. The lower clamping-bar at the base of the apparatus is made wider than the others, to increase the support and facilitate the detaching of the desk from the instrument when desirable. The thumb-screw may be left out in the manufacture, or, if made, may be used or not, at the pleasure of the performer. It may also be made of any desirable size, so that it does not project too far up against the piano lid when down. The inner edges of the clamping-bars may be cushioned in the usual manner, to take up the shock of closing, and other parts may be cushioned also in the common way, to prevent rattle in playing.

The advantages of my invention are the means of adapting the distance of the music to the focal distance of the eye, and the changing conditions of the light at the time, but more particularly in extending the desk in the proper line of vision *k*, fig. 3, instead of the line *m*. It also relieves the player of the necessity of stooping to bring the eye to *l*, cramping the body, and bringing the elbows below the key-board, and producing an inelegant attitude, besides rendering the play difficult. Another important advantage is in the uniform working of the movable parts of the desk, which in those now in use are apt to cramp in the wooden ways, and can only be moved by violent effort, at times causing the rapid destruction of the apparatus, or the neglect to use it altogether, only as an immovable desk, because of the annoyance in the working. This has become apparent to so great an extent that the movable desk has gone nearly out of use. Every change in the atmosphere of the room, whether thermal or hygrometric, affects the working, and it can never be depended on, and as some windage at the ends is absolutely necessary on this account, the very windage itself becomes an element of trouble, and unless the foot-board is grasped exactly in the centre, and pulled with extreme care, it is almost sure to jam and fail. But notwithstanding the disadvantages, the imperfect movable desks in use have been clung to by some manufacturers, showing that the want of a good desk is very much felt. In the use of the immovable desk the near-sighted player must strain forward to see, and the long-sighted also when the light is not strong enough. Another advantage of my desk over the horizontal movable racks, is, that the foot-board *d*, which in the common desk would project over the key-board, in this case rises obliquely above it, neither obstructing the hands nor the sight. Neither does the invention materially increase the expense of the manufacture. The extension of the desk forwards and upwards can be stopped at any point, and can be readily moved with one hand while playing, scarcely interrupting the player's hand for a moment, while the other movable racks require more time and both hands. The use of this removes the necessity for the unsightly angles about the front and top of the piano, and the long bridges or guides projecting over the strings, on which the old movable desks are made to move, obstructing and breaking up the sound. As the working parts are of metal, they are less liable to bind from the causes named.

What I claim as my invention, is—

The cross-bars *G*, in combination with the clamping-bars *e*, the inclined plane *h*, thumb-screw *f*, slots *p*, spurs *o*, enlargements *n*, and also in combination with the other common devices, such as the foot-board *d*, rack *e*, and instrument *a*.

FRANCIS XAVIER RIZY.
